AUTOMATIC BARREL STACKER AND
DISPENSER

William E. Ross, Milwaukee, Wis.

Application April 19, 1937, Serial No. 137,807

3 Claims. (Cl. 193—32)

This invention relates to apparatus for filling, stacking and transferring barrels or kegs of beer and other liquids.

The object of the invention is to provide an automatic barrel stacker of inexpensive and durable construction especially designed for installation in breweries and similar places and by means of which barrels, kegs and other containers, after being filled with beer and properly bunged or sealed are caused to travel down inclined trackways to the discharge end of the stacker for delivery to a truck or other conveyance, thereby obviating the disorder and confusion usually incident to the filling and handling of barrels or kegs in breweries under present methods.

A further object of the invention is to provide the stacker with a novel form of brake for retarding and controlling the movement of the barrels or kegs on the inclined trackways and preventing jamming of said barrels so that the barrels will roll smoothly and uniformly on the tracks from the intake end of the stacker to the discharge end thereof.

A further object is to provide the discharge end of the stacker with a foot actuated tripper member so disposed with relation to the adjacent track that, when said member is in one position, it will act as a stop or barrier to prevent the discharge of the kegs or barrels from the stacker and when in another position will receive one of the barrels thereon and from which member said barrel may be transferred to a delivery truck, the removal of the barrel from the tripper member serving to automatically return said tripper member to normal position so as to prevent the discharge of another barrel until the tripper is again actuated by the foot pedal.

A further object is to arrange the inclined tracks in superposed relation with opposite ends of adjacent tracks connected by curved plates which serve to guide the barrels from one track to another without undue friction thereon.

A still further object of the invention is generally to improve this class of apparatus so as to increase its utility, durability and efficiency.

In the accompanying drawings forming a part of this specification and in which similar numerals of reference indicate corresponding parts in all the figures of the drawings:

Figure 1 is a side elevation of one unit of a filling, stacking and transferring apparatus constructed in accordance with the present invention showing the apparatus in juxtaposition to the barrel filling mechanism,

Figure 2 is a top plan view,

Figure 3 is an enlarged side elevation, partly in section, of the forward end of the apparatus,

Figure 4 is a horizontal sectional view taken on the line 4—4 of Figure 3,

Figure 5 is a vertical sectional view taken on the line 5—5 of Figure 3,

Figure 6 is a perspective view of one of the braking members and its associated parts detached,

Figure 7 is a transverse sectional view of one of the brake shoes,

Figure 8 is an enlarged side elevation, partly in section, of the discharge end of the apparatus,

Figure 9 is a horizontal sectional view taken on the line 9—9 of Figure 8,

Figure 10 is a transverse sectional view taken on the line 10—10 of Figure 9 showing the tripper member in position to act as a stop or barrier for the barrels on the stacker, and

Figure 11 is a similar view showing the tripper member in position to receive one of the barrels from the stacker.

The improved automatic barrel stacking apparatus may be constructed in any desired number of units according to the capacity of the brewery in which it is installed and the number of dispensing faucets employed, it being preferred to mount a single unit opposite each dispensing apparatus, and in Figure 1 of the drawings, I have shown a single unit disposed in juxtaposition to the barrel filling mechanism, indicated at 5.

The apparatus comprises a structural iron framework consisting of upper, lower and intermediate longitudinal sills 6, 7, and 8, respectively, preferably formed of angle iron and riveted, welded or otherwise rigidly connected by vertical braces

9 also preferably formed of angle iron, as shown, said longitudinal sills defining superposed runways 10, 11, and 12 for the passage of barrels, kegs or other containers, indicated at 13. The longitudinal sills of the framework are connected at spaced intervals by transverse sills 14 on which are mounted standard tracks 15, the tracks of each runway being slightly inclined so as to permit barrels deposited on the intake portion of the upper runway 10 to roll down the several tracks to the discharge end of the apparatus, as will be more fully explained hereinafter. The

forward end of the apparatus is provided with a receiving table 16 connected to the adjacent vertical sills 9 by an inclined brace 17 and the upper portion of this table is provided with up-

standing guard flanges 18 to prevent displace-

ment of a barrel when placed in position thereon. Guide flanges 19 are also preferably secured to the intermediate longitudinal sills 8 at the forward end of the apparatus, and inclined braces 20 are disposed beneath the flanges 19 and connected to the adjacent uprights 9 to assist in reinforcing the structure. The ends of the tracks of the upper runway 10 are preferably curved downwardly, at 21, so as to present a smooth 10 curved surface for contact with the barrels while the tracks of the runway 11 at the rear end of the apparatus are curved upwardly and forwardly, as indicated at 22, so as to form guides for directing the barrels from the upper runway 10 15 onto the tracks of the runway 11. The forward ends of the tracks of the lower runway 12 are curved upwardly and rearwardly, as indicated at 23, to form curved guides similar in construction to the guides 22 and which serve to direct the 20 barrels from the runway 11 onto the tracks of the lower runway 12. The tracks on the runway 11 are also preferably curved downwardly and laterally, as indicated at 24, so as not to interfere with free movement of the barrels or kegs 25 in their passage from one runway to the other. The rear or discharge end of the stacker is preferably reinforced and strengthened by the provision of diagonal braces 25 having their ends riveted or otherwise secured to anchoring plates 30 26 mounted on the adjacent uprights 9 and their points of intersection secured to a bridge plate 27, as best shown in Figure 8 of the drawings.

In order to retard or control the passage of barrels or kegs in the different runways, I have 35 provided suitable brakes 28 and 29, one of which is mounted in the runway 11 for contact with the barrels rolling therethrough and the other mounted in the runway 12 for contact with the barrels on their passage through said runway to 40 the discharge end of the apparatus. The brakes 28 and 29 each comprises spaced longitudinally disposed shoes 30 having their lower faces covered with any suitable brake lining material 31 and as both brakes and the shoes carried thereby 45 are of similar construction, with the exception of the location of their pivotal points, a description of one will suffice for both. The forward ends of the shoes 30 of the brake 29 are welded or otherwise rigidly secured to a connecting yoke 32 while the rear ends of the brake shoes are pivotally mounted at 33 on transverse angle irons 34 extending beneath the rails of the runway 11 so that said brake shoes when depressed will bear against the barrels in the runway 12. Pivotally mounted at 35, on the opposite ends of the yoke 32 are suspension links 36, the upper end of one of which is pivotally connected, at 37, to the short end of a bell crank lever 38, while the end of the other link is pivotally connected to 50 a crank arm 38'. The bell crank lever 38 and crank arm 38' are connected by a bar or rod 39 extending transversely of the framework and pivotally mounted, at 40, on the long arm of the bell crank lever 38 is an actuating rod 41 which 55 extends longitudinally of the apparatus on one side thereof and is provided near its terminal with spaced teeth or serrations 42 for engagement with a latch plate 43. The actuating rod 41 is provided with a terminal handle 44 so that 60 by elevating the handle end of the rod until the teeth 42 clear the latch plate 43 and exerting a longitudinal pull on the actuating bar the bell crank lever 38 will be tilted and thus force the yoke 32 carrying the brake shoes 30 down- 65 wardly in the path of the barrels on the stacker 70 75

for the purpose of arresting or entirely stopping the passage of said barrels when desired. Similar actuating rods 45 extend from the brake shoes of the brakes 28 to the rear portion of the apparatus, as shown, so that the brakes 28 and 29 can be actuated either simultaneously or successively as the occasion may require. 5

Secured to the opposite sides of the supporting frame at the discharge end thereof are spaced plates 46 between which is pivotally mounted 10 for tilting movement a tripper member 47. The tripper member 47 comprises a transverse shaft 48 pivotally mounted in the side plates 46 and to which is rigidly secured spaced blocks 49, the upper faces of which are curved to form a seat 15 for the barrels or kegs. Disposed beneath the tripper 47 and spaced therefrom are rails 50 constituting rests or supports for said tripper member and connected with the rear ends of the blocks 49 is a substantially L-shaped bar 51 20 adapted to rest on the adjacent transverse rail 50 when the tripper is moved to a position to receive one of the barrels from the adjacent runway. It will thus be seen that the rear transverse track 50 by engagement with the L-shaped bar 51 serves to limit the pivotal movement of the tripper in one direction while a bar 52 connecting the blocks 49 by engagement with the other track 50 serves to limit the pivotal movement 25 of the tripper in the other direction. Secured 30 to one end of the transverse shaft 48 is a crank arm 53 to which is pivotally connected, at 34, the adjacent end of a foot pedal 55, said pedal being pivotally mounted at 56, on the adjacent plate 46 and provided with a terminal tread 35 surface 57. Under normal conditions, the tripper 47 will be in the position shown in Figure 10 of the drawings, that is to say, with its rear end extending upwardly in front of and above the plane of the tracks of the lower runway 40 12 so that said tripper acts as a stop or barrier to confine the barrels in position on the stacker. When the lever 55 is depressed with the foot, however, the rear end of the tripper will be swung 45 downwardly on its pivotal axis to a position in alignment with the tracks of the lower runway, as best shown in Figure 11 of the drawings, and in which position one of the barrels in the lower runway will engage the concave seat of the tripper so as to permit an attendant to readily 50 remove a keg or barrel therefrom and deposit the same in a delivery truck or other conveyance. As the barrel is removed from the tripper, said barrel will bear against the forward end of the tripper and thus return the tripper to the position shown in Figure 10 of the drawings and in 55 which position the rear end of the tripper will prevent further delivery of the barrels until the foot pedal is again operated.

As previously stated, the stackers may be constructed in gangs or units, each unit consisting of one or more of the stackers and their associated parts and in installing the stackers in a brewery, said stackers are positioned in front of and adjacent to the beer dispensing apparatus 5. Under 60 the present procedure of filling barrels or kegs with beer in breweries, it is customary to fill the barrels at the dispensing faucets and then throw or kick the barrels to one side with the result that the floor of the brewery soon becomes littered up 65 with filled barrels necessitating their constant removal in order to provide space for the operators to perform their duties. If the barrels are not removed immediately after being filled, they will 70 soon accumulate in large quantities on the floor of 75

the brewery and materially interfere with the workmen. According to the present invention, an empty barrel or keg is placed on the receiving table 16 and filled with beer from the dispensing apparatus and the filled keg properly bunged or sealed. As the kegs are successively filled, they will roll by gravity down the upper runway 10 onto the runway 11 and thence to the runway 12, being guided in their passage at the ends of the tracks by the curved shields 22 and 23. The runways will soon become filled or partially filled with barrels and the first barrel placed on the receiving table will ultimately roll to a position in contact with the end of the tripper 47 where further movement thereof will be arrested. During the passage of the barrels in the different runways, it often happens that the motion of said barrels will become accelerated to such an extent as to cause jamming thereof and in this event the movement of the barrels can be retarded or entirely arrested by actuating the brakes 28 and 29 which, as before stated, will frictionally bear against the barrels in the adjacent runway and hold them against further movement until the congestion is relieved. The barrels at the discharge end of the stacker may be individually and successively removed therefrom by depressing the foot pedal in the manner previously described so that, while one barrel is being transferred from the tripper 47 to a delivery wagon, there is no danger of any of the other barrels in the stacker being accidentally discharged or released therefrom.

It will, of course, be understood that the devices may be made in different sizes and shapes and provided with any desired number of brakes without departing from the spirit of the invention. It will also be understood that where several of the beer dispensers are disposed in close proximity to each other the tracks of certain of the runways may be curved inwardly from the outer ends of the stackers towards said dispensing apparatus so as to conserve space in the brewery.

From the foregoing description, it is thought that the construction and operation of the device will be readily understood by those skilled in the art and further description thereof is deemed unnecessary.

Having thus described the invention, what is claimed as new is:

1. An apparatus of the class described comprising a supporting frame, an inclined barrel runway mounted on the frame, spaced tracks forming a part of said runway, a tripper member pivotally mounted on the frame at the discharge end of

the runway and including spaced blocks having their upper faces concaved, a shaft carrying said blocks and rotatably mounted transversely of the runway, front and rear transverse bars connecting the blocks, spaced rests disposed beneath the tripper member in position to be engaged by said bars and support the tripper in adjusted positions, a crank arm fixed to said rocker shaft and extending laterally therefrom, and a foot pedal operatively connected with the crank arm for rotating the shaft and adjusting the tripper member, the front transverse bar by engagement with one of the rests serving to support the tripper member in a discharging position with inner ends of the blocks in the path of the barrels in the runway and the rear transverse bar by engagement with the other rest serving to support the tripper member in an upright position with inner ends of the blocks in alignment with the tracks of the adjacent runway to permit the passage of a single barrel from said runway onto the blocks of the tripper member.

2. In an apparatus of the class described, a supporting frame, an inclined barrel runway mounted on the frame, spaced brake bars pivotally mounted at one end on the frame within the runway, a connecting yoke secured to the free ends of the brake bars and extending transversely thereof, a rocker shaft rotatably mounted transversely of said frame, lever arms carried by said shaft, links connecting said arms with ends of said yoke, an operating rod operatively connected with one lever arm and extending longitudinally of the frame, and a keeper for holding the rod in an adjusted position.

3. In a device of the class described, a supporting frame, an inclined barrel runway mounted on the frame, brake bars spaced transversely from each other and pivotally mounted on the frame within the runway, a yoke extending transversely across and secured to said brake bars, a rod extending transversely of the frame and rotatably mounted therein, a bell crank lever carried by one end of the rod and having one arm longer than the other, a radial arm carried by the other end of the rod, an operating lever connected with the long arm of the bell crank lever and leading to an end of the frame, a link forming a pivotal connection between one end of the yoke and the short arm of the bell crank lever, and a second link forming a pivotal connection between the other end of the yoke and the radial arm on said rod.

WILLIAM E. ROSS. 55
